(57) CLAIM

I claim the ornamental design for the shelving unit, substantially as shown and described.

DESCRIPTION

FIG. 1 illustrates a top view of a shelving unit showing my new design;

FIG. 2 illustrates a perspective view thereof;

FIG. 3 illustrates a front elevational view thereof; and,

FIG. 4 illustrates a right side view thereof and the left side is a mirror image thereof.

1 Claim, 1 Drawing Sheet

FIG. 1

FIG. 2

FIG. 4
